UNITED STATES PATENT OFFICE.

DUNCAN KENNER, OF NEW ORLEANS, LOUISIANA, ASSIGNOR TO DRY HAND MOP COMPANY, OF NEW ORLEANS, LOUISIANA, A CORPORATION.

MOP.

1,426,084.

Specification of Letters Patent. Patented Aug. 15, 1922.

Application filed November 1, 1920. Serial No. 421,047.

To all whom it may concern:

Be it known that I, DUNCAN KENNER, a citizen of the United States, and a resident of New Orleans, parish of Orleans, and 5 State of Louisiana, have made certain new and useful Improvements in Mops, of which the following is a full and complete specification.

My invention relates to a novel improvement 10 in the construction and assemblage of mops, it being a feature of my device to provide a mop head so arranged upon a handle that after use the mop may be wrung out and the superfluous water drained from the 15 mop head without the operator's hands becoming wet in the operation.

Where mop heads have been attached to the ends of handles in such manner as to permit of their being wrung dry without 20 removing from the handles, the wringing device together with the attaching means is customarily formed of metal or so shaped as to expose its projecting parts beyond the mop head. This results in frequent injury 25 to the floor or furniture with which the mop comes into contact and causes scratches. Hence, it is an object of my invention to insure that the mop head extends beyond the mop handle at all times in such a way as to 30 prevent damage to any object with which the mop head may ordinarily be brought into contact.

It has been found in the use of this type 35 of device that where the loose strands are free to move relatively to each other during the mopping operation, the strands are likely to become tangled and interfere with the proper wringing out of the water. It is, therefore, a feature of my invention to arrange 40 the mop head with respect to the handle in such fashion that the fibrous material of the mop head is retained in orderly strands, in fixed relative position and secure against entanglement.

45 Other objects of my invention will be apparent from the following description and drawings, in which latter:

Fig. 1 shows a mop in operative position,

50 Fig. 2, the mop arranged for wringing, and

Fig. 3, an enlarged fragmentary view of the lower portion of the mop handle carrying a mop head, as in Fig. 1.

55 A handle 5 of suitable length is provided at one end with a knob or other device 6

easily grasped by the hand. The handle 5 is reduced for a portion of its length as at 7 between the shoulder 8 and the end 9. A coiled wire or other metallic helix 10 is arranged upon the reduced portion of the handle 5, being fastened at the lower end as at 11. The wire coil is free to move longitudinally and circumferentially, there being no fastening means connecting it at the upper end with the handle and its limit of movement is controlled only by the shoulder 8. This coil 10 is of slightly greater diameter than reduced portion 7 of the handle for a purpose as will appear hereinafter.

60 A tubular sleeve 12 with a hole 13 parallel to its length and large enough to slide over the coiled wire is provided and has a bead 14, while the lower portion is turned outwardly as at 15.

The mop head shown in the preferred 75 form consists of a large number of loops of yarn or other fibrous material, the ends 16 of which are fastened to the movable tubular sleeve preferably above the outwardly turned portion 15, by means of a binding 17. 80 Each loop of yarn consists of an outer and inner length extending to a bight arranged beyond the end, 9, of the handle, 5. The bights of these loops are bound together by a fastening, 18, which may be of wire, yarn 85 or fibrous material. The strands of yarn divide radially from the binding, 18, and are carried around the end, 9, of the handle in outer and inner courses, being fastened tightly to the end, 9, and over the end of the 90 coil, 10, by means of a wrapping, 19.

Twine, thread or a strand of yarn is woven or stitched through the parallel adjacent lengths of the loops, as indicated at 20 and 21. This stitching divides the 95 lengths into three substantially equal parts. It will be evident that during the mopping operation the bent or middle part of the head is free to conform to the floor and the strands will separate as is desirable. 100 At the same time the end portions are capable of spreading into a fan shape, due to the length of the stitching. At the points of stitching 20 and 21, the lengths of the loops are brought from their superposed position 105 radially of the handle into a position side-by-side and circumferentially of the handle. The strands are therefore maintained in contiguous relation secure against relative movement, or separating and tangling.

When the handle 12 is raised to extend the strands around the helix 10 preparatory to the twisting and wringing movement, the stitching 20 and 21, serves to maintain the strands in definite and prearranged order. Where no stitching is used it has been found that the mopping movements will transpose a strand so that the raising of the handle 12 brings the displaced strand 10 obliquely around the fabric structure, preventing the proper movement of the handle 12 longitudinally or circumferentially of the member 7.

By making the coil 10 slightly larger than the reduced portion of the handle there is no binding between the two and the parts of the coil are free to move with the mop as the latter is twisted. After the twisting is completed and the mop has had most 20 of the water wrung out, there is a tendency on the part of the mop to mat or cling to the reduced portion of the handle. The resilience of the coil will cause it to expand, thus lifting the mop strands free and facilitating their return to operative position. 25 As the coil is never actually compressed to the diameter of the reduced portion of the handle, there is always a small space between the two, through which the water can 30 pass after having been wrung out.

A mop constructed as above described is found to protect any object with which it comes in contact such as the floor and furniture from injury by adequately sheathing 35 the mop handle and wringing attachment. The form of mop head is effective to extend in all directions, spreading out and exposing all sides of the individual strands. During this operation the end parts between 40 the stitching and the bindings assume fan shapes. The wringing out of soiled water is made certain by the restoration of the parallel positions of the strands as the handle 12 is raised and twisted, the stitching 45 20 and 21 preventing lateral displacement of the individual strands.

While I have described a preferred form for my invention it is obvious that many changes may be made without departing 50 from the spirit of the invention and within the scope as defined in the appended claims.

What I claim is:

1. In a mop, the combination of a handle, a mop-head consisting of a plurality of 55 loose strands having loops brought together

beyond the end of the handle, means securing the strands around the ends of the handle, a hand-grip movable over the handle and carrying the free ends of the strands.

2. In a mop, the combination of a handle, 60 a mop-head consisting of a plurality of loose strands brought together beyond the end of the handle, means securing the strands around the end of the handle, a hand grip movable over the handle and 65 carrying the free ends of the strands, and means intermediate the ends of the strands for limiting the spread of the strands.

3. In a mop, the combination of a handle, 70 a mop-head consisting of a plurality of loose strands brought together beyond the end of the handle, means securing the strands around the end of the handle, a hand-grip movable over the handle and carrying the free ends of the strands, and 75 a plurality of connecting means equidistantly disposed on the mop-head for maintaining the adjacent strands thereof in contiguous relation at the points of connection.

4. In a mop, the combination of a handle, 80 a mop-head consisting of a plurality of loose strands brought together beyond the end of the handle, means securing the strands around the end of the handle, a hand grip movable over the handle and 85 carrying the free ends of the strands, and connecting means intermediate the ends of the mop-head for maintaining the strands thereof in contiguous relation at the point of connection. 90

5. In combination with a handle and hand-grip, a mop-head formed of separate strands of fibrous material arranged in adjacent relation around the said handle, the end portions of said strands being fastened 95 to said handle and hand-grip, and the intermediate portions of adjacent strands being bound together.

6. In combination with a handle and hand-grip, a mop-head formed of separate 100 loose strands having loops of fibrous material arranged in adjacent relation around the said handle the bights and ends of said strands being fastened to said handle and hand-grip respectively, and the intermediate 105 portions of adjacent strands being bound together.

In witness whereof I have hereunto affixed my signature.

DUNCAN KENNER.
